SPIRIT STOVES

Karl Oskar Arne Boij, Agatan 5, and Bertil Karl Axel Johansson, Agatan 26, both of Tranås, Sweden

Filed Feb. 1, 1957, Ser. No. 637,741

1 Claim. (Cl. 126—43)

The present invention relates to apparatus operating by burning alcoholic spirits or similar kinds of liquid fuels—in the following description and appended claims termed “spirit stoves”—and of the kind consisting of a fuel container made of metallic or any other suitable material and containing a filling of a porous material absorbing the fuel, and having a plurality of flame apertures provided in circumferentially spaced relation in the upper portion of its side walls.

The primary object of the present invention is to provide an improved spirit stove of the kind referred to which combines an extremely simple construction with the favorable properties of being capable of convenient storage without any danger of escape or leakage of the fuel contained in the stove, further: of being ready for use at any time, and of being adapted to be lit quickly without the necessity of being preheated.

A further object of the invention is to provide a spirit stove of the kind referred to which is devoid of any enclosed air spaces in which explosive gas mixtures might form.

A spirit stove which satisfies the requirements thus stated has been realized in accordance with this invention by causing the porous material to fill up completely the upper portion, at least, of the fuel container, so that the same will reach and bridge the flame apertures, and by dimensioning these flame apertures sufficiently large to enable the stove to be lit without any preparatory preheating.

The spirit stove according to the invention in its simplest form consists of a tin-like, permanently closed container which is filled with a porous material saturated with liquid fuel and exposed near the upper end of the container through relatively large flame apertures formed in the peripheral wall of the container in close proximity to the flat top surface of the same, on which top surface a cooking vessel can be placed. In this embodiment of the invention the stove can be produced at a cost sufficiently low to justify its being discarded after its initial charge of fuel has been consumed. It is possible, however, if desired, to refill such a stove with a fresh charge of fuel through the flame apertures. In case the stove is to be refilled repeatedly the fuel container may, however, to advantage be provided with a removable bottom, so that refilling may be effected through the bottom and after the fuel container has been turned upside down and its detachable bottom removed.

The flame apertures, which preferably are rectangular in shape and comparatively large, can be covered by a sheet of wire gauze which acts to prevent the porous filling from escaping through the flame apertures, as well as from getting forced inwards by external action in conjunction with the handling of the apparatus. However, if that portion, at least, of the porous filling which reaches onto the flame apertures is formed by a permanently shaped body or disc fitted into the container and consisting of felted mineral wool or the like, then

the flame apertures can be left completely open and unobstructed.

Further features and advantages of the invention will appear from the following detailed description of two embodiments thereof by way of example, reference being had to the accompanying drawing, in which

Fig. 1 is a perspective view of a spirit stove according to a preferred embodiment of the present invention, a fire quenching or extinction hood belonging to the stove being, however, omitted from the figure;

Fig. 2 is a vertical section through the spirit stove illustrated in Fig. 1 but with the extinction hood placed in position thereon, and

Fig. 3 is a perspective view of a second embodiment of the invention.

Referring first to Figs. 1 and 2 of the drawing, reference numeral 10 designates the metallic fuel container which is in the form of a cylindrical tin the upper end of which is closed by a flat top-end wall while its bottom end is left open. The fuel container 10 is provided in the upper portion of its peripheral side wall with three comparatively large flame apertures 11 which are uniformly spaced circumferentially of the peripheral wall. These apertures are covered by a sheet of wire gauze 12 which is in the form of a peripherally closed ring disposed within the container and in close contact with the inner surface of its peripheral wall. Received in the interior of the container 10 is a porous filling or matrix 13 consisting of compacted mineral wool, for instance asbestos wool, which reaches and bridges the flame apertures 11 but is prevented by wire gauze 12 from escaping through these apertures. Further below, the porous filling is formed by a porous and permanently shaped disc 14 made of wood fiber or similar material and retained within the container by friction against its peripheral wall so as to prevent the filling 13 of asbestos wool from escaping through the bottom end of the container.

The bottom end of the fuel container 10 is closed by a detachable bottom cover 15 formed with a peripheral flange 16 fitting about the peripheral wall of the container 10. The said bottom cover 15 is retained in place by four embossments 17 circumferentially spaced about said wall and engaging said peripheral flange. The bottom flange 16 is extended as far upward towards the bottom edges of the flame apertures 11 as to cause any gasified fuel escaping through the bottom opening of the container 10 to be conducted into close proximity of the flames to be ignited by the latter. It is preferable to let the bottom flange 16 terminate short of—for instance 0.4 to 0.8 inch below—the bottom edges of the flame apertures, in order thereby to reduce the heating of the bottom part of the apparatus. Inserted in the bottom cover 15 is a filling consisting of a porous disc 18 of wood fiber or similar material which, when the bottom cover is fitted in place on the fuel container, projects into the interior of the container and engages the wood fiber disc 14 pressed into the cylindrical wall thereof so that—when the stove is ready for use—the container 10 is completely filled with porous material.

Refilling of the container 10 with liquid fuel is performed in the most simple way by first turning the stove upside down, then removing its detachable bottom cover 15, 16, and finally pouring fuel into the cup defined by the wood fiber disc 14 and the portion of the cylindrical container wall projecting above this disc. In order to accelerate the fuel-absorption by the mineral wool matrix 13, the wood fiber disc 14 may be provided with a plurality of openings 19 through which fuel is allowed to flow directly down to the mineral wool matrix.

The lighting of the spirit stove illustrated is per-

formed by simply putting a burning match to each one of the flame apertures 11. The spirit stove can be extinguished by putting over the top portion of the fuel container 10 a hood-like cover 20 the peripheral wall or flange of which telescopes within the flange 16 of the detachable bottom cover, as is clearly seen from Fig. 2. For facilitating the handling of the hood 20 a handle 22 is pivotally connected thereto by a rivet 21. Any fuel condensing on the comparatively cool internal wall surfaces of the hood 20—particularly immediately following the extinction of the stove—will gravitate to the bottom of the apparatus where the same will be absorbed by the porous bottom disc 18 and will be returned gradually by capillary action to the porous filling or fuel matrix 14, 13 within the container 10. The free upper edge of the flange 16 of the detachable bottom cover may be flared outwardly in a funnel-like manner which will, on one hand, facilitate the action of pushing down the hood 20 within the bottom flange 16, and, on the other hand, make sure that condensed fuel shall not—even if the hood be incompletely applied—flow over the external wall surface of the bottom flange 16.

It is apparent that the hood 20 when applied in position within the bottom flange 16 forms with the bottom cover 15, 16 a sealed-off storage casing for the fuel container 10, whereby fuel contained in the latter is prevented from vaporizing when the spirit stove is being stored.

The flame apertures 11—in the embodiment illustrated—are disposed short of the flat top of the fuel container enabling a cooking vessel to be placed directly on to the fuel container. To enable the cooking vessel to stand steadier, the fuel container may be formed with a pressed up or creased rim 23 along the corner between its cylindrical wall and its flat top wall.

For the safe handling of the apparatus by the hand serves a heat insulating ring 24 of rubber or similar material which is forced on the flange of the bottom cover.

The embodiment illustrated in Figs. 1 and 2 may be modified in various respects. Thus the wire gauze 12 may be omitted if that portion, at least, of the porous filling which extends behind the flame apertures is made more or less permanent in shape, consisting, for example, of a disc punched out from a felted sheet of mineral wool so as to fit within the fuel container. Further, the porous disc 14 retaining the filling in position within the fuel container may be substituted by a perforate sheet-metal disc which is secured in position within the container by spot welding or in any suitable other manner.

Referring now to Fig. 3 of the accompanying drawing, the spirit stove according to the embodiment illustrated therein is simply made in the form of a permanently closed parallelepipedic fuel container 25 which contains a porous filling or matrix saturated with al-

coholic spirits or similar liquid fuel and reaching and bridging two rectangular flame apertures 26 provided in the upper portion of the elongated side walls, respectively. When the stove is not in use, the flame apertures 26 can be closed and sealed off by means of an endless strip of rubber or like material which may be forced on to the peripheral wall of the container 25. The spirit stove illustrated in Fig. 3 is primarily intended to be sold with its matrix saturated with liquid fuel and to be discarded as soon as the charge of fuel has been consumed. The porous filling or matrix, therefore, to advantage, may be formed throughout by compacted wood fibers or any suitable other non-refractory porous material. However, refilling of the apparatus with a charge of fresh fuel can be made through the flame apertures 26, if desired.

What we claim is:

A spirit stove comprising a container having side walls and a top wall and an open bottom, porous fuel absorbing material packed in said container and completely filling the upper portion thereof thereby to eliminate spaces in which explosive gas mixtures might accumulate, a cup-shaped cover detachably slidably fitted over the bottom of said container having its side walls extending about the side walls of said container in spaced relation thereto and terminating a substantial distance below the top of said container, said porous fuel absorbing material being exposed through large openings in the side walls of said container, said openings being immediately above the rim of said cup-shaped cover and being of a size to enable the stove to be lit without the necessity of being preheated, a cup-shaped cover fitted over the top of said container having its side walls detachably slidably fitted to the side walls of said bottom cover, and a porous member affixed to the bottom cover of the container positioned to extend into said container when the bottom cover is in position thereon and providing a space in said container when the cover is removed therefrom for the reception of fuel and serving to absorb condensate gravitating downward from said first cup-shaped cover.
